T. M. SMITH,
SIGNAL FOR AUTO DRIVERS,
APPLICATION FILED DEC. 18, 1916.

1,253,104.

Patented Jan. 8, 1918.

Inventor:

Thomas Marshall Smith,
Dear Isadore Donaldson & Dear
Atty's.

UNITED STATES PATENT OFFICE.

THOMAS MARSHALL SMITH, OF BALTIMORE, MARYLAND.

SIGNAL FOR AUTO-DRIVERS.

1,253,104.

Specification of Letters Patent.

Patented Jan. 8, 1918.

Application filed December 18, 1916. Serial No. 137,693.

To all whom it may concern:

Be it known that I, THOMAS MARSHALL SMITH, a citizen of the United States, and resident of Baltimore, Maryland, have invented certain new and useful Improvements in Signals for Auto-Drivers, of which the following is a specification.

My invention relates to signaling devices whereby the driver of an automobile may give a signal at night by a motion of his arms similar to that which is required by the police regulations in many localities to indicate when the driver intends to stop the machine or make a turn and in carrying out the invention an electric lamp is carried on the arm of the driver so that the driver of the following automobile may readily see the signal at night.

The invention consists in the features of combination and arrangement of parts hereinafter described and particularly pointed out in the claims.

In the accompanying drawings:

Figure 1 is a side elevation of the device attached to the sleeve of the user, and

Fig. 2 is an elevation of the device at a quarter turn from that shown in Fig. 1.

Fig. 3 is a sectional view taken transversely of the casing and its supporting bracket.

In the drawings 1 indicates an incandescent electric light globe carried by the body 2 of substantially the same form as is in commercial use and to this lamp wires 3, 4 are connected, these being surrounded by suitable insulation at 5 at their point of juncture with the lamp body. This lamp is held within a barrel or casing 6 having a closed end at 7 and having a cap 8 to close its open end, this cap being provided with an opening 9 for the passage of the conductor wires 3, 4. The casing or barrel has a laterally disposed opening 10 through which the light may be observed. For giving a red signal I use a glass tube 11 open at both ends and fitting closely to the interior walls of the casing or barrel, this glass tube receiving within it the electric lamp and serving as a protection or shield to the bulb thereof. This glass extends from end to end of the casing and abuts against the head or closed end 7 and as it covers the lateral opening 10 and has the light back of it this light will show through the red glass exposed at this lateral open-

ing 10 and thus the color red will be displayed, indicating danger.

The glass tube may be slipped into the casing and is held by the cover 8 which in turn slips onto the outer side of the rear end of the casing, where it may be retained by friction or by a nib 12 fitting friction-tight into a depression 13 formed in the cover. The insulation 5 surrounding the lamp body insulates it from the cover 8 and this insulation fits closely in the end of the glass tube and serves to center the lamp.

The barrel or casing is supported in a sheet metal bracket 14, which may be of substantially circular form with its ends passing through an opening in the upper arm 15 of a clamping member and the bracket may be held by solder at this point. The circular main body portion of the bracket embraces the barrel or casing of the lamp fitting for this purpose between ribs 16 on the barrel, by which the barrel is prevented from having longitudinal movement in relation to the bracket but may be turned about its axis in said bracket for a purpose hereinafter described.

The device may be attached to the glove of the driver or a wrist strap or to the edge of his sleeve at the wrist by means of a clamp of substantially ordinary form, such as shown in the drawing, which includes the upper and lower members 15, 16 pressed together by a spring clip 17 of substantially cylindrical form, this spring clip also acting as the main body of the clamp and holding the upper and lower members in proper relation to each other. The cylindrical spring clip, as just stated, is in tubular or cylindrical form and as shown in Fig. 1 extends with its axis at right angles to the axis of the casing of the device and it will be noticed that the clamping jaws are of considerable extent so that firm clamping engagement may be secured by these jaws upon the edge of the sleeve of the coat of the driver. The lower member 16 of the clamp is provided with a finger-piece or button 18, made of celluloid, fiber or other substance that will provide a good gripping surface for the fingers in manipulating the clamp and will also furnish a smooth surface to avoid abrasion of the hand of the user. The relation of the tubular casing containing the lamp to the clamp is such that the said casing forms in effect an ex-

tension of the upper member of the clamp and the operator in applying or removing the clamp will naturally grasp the button 18 with his thumb and the tubular casing with his finger and by reason of the long leverage provided by the casing forming an extension of the clamping arm the clamp may be readily manipulated or of course the thumb may be applied to the casing and the finger 10 to the lower clamping member 16.

In order to prevent undue strain coming upon the lamp tending to withdraw the head 8 I provide a support intermediate of the end of the lead wires where they attach to the 15 contact plug and the lamp and I mount this support as shown in Fig. 1 on the arm of the user at 19. This support may be in the form of a spring clip having an opening through which the lead wires extend at 20 and by reason of this support the stretch of wire between it and the lamp is not subjected to any strain or lateral displacement, tending to cant the device from its position. All strains which may be put upon the lead wires 25 at points between the support 19 and the battery will be taken up by this support and prevented from being communicated to the lamp and the cover 8, so that this cover readily may be held in place by friction 30 alone.

As above stated the casing may be rotated within the bracket 14 and thereby the display opening 10 may be positioned to the right or left-hand side of the device to suit either style of car, right-hand control or 35 left-hand control.

The edge of the opening 9 in the cap 8 is turned outwardly so as to prevent the raw edge of this opening from abrading the insulation of the lead wires 3, 4.

It will be understood that the wearer of the device need only position his arm or wave his arm carrying the lamp and thereby give a signal to a following automobile or 40

to a crossing policeman to indicate danger to 45 the following automobile or the direction he intends to take to the crossing policeman.

The glass tube not only acts as a protector for the glass globe of the lamp but will insulate the lamp body from the casing. 50

The casing may be held in its different positions within the bracket by a nib on the casing entering depressions on the bracket, as indicated at α , it being understood that there is one of these depressions for each position of the casing. 55

What I claim is:

1. In combination an electric lamp, a casing inclosing the same and having its axis coinciding with that of the lamp, a clamp 60 consisting of two members on one of which the casing is directly mounted to move therewith as one body, said clamp attaching the casing to the user with the axis of the casing parallel with the axis of his arm, wrist, or 65 hand, lead wires extending to the lamp through the rear end of the casing, said casing having a lateral opening for the display of light and means for holding the lead wires at a point in rear of the lamp and substantially co-axial therewith, the said means being adapted to be supported on the arm of the user, substantially as described. 70

2. In combination an electric lamp, a revoluble cylindrical casing inclosing the same 75 and having a single opening in its lateral wall, leaving the opposite wall intact to serve as a reflector, a clamp composed of two movable members, one of which is at its end provided with an upstanding bracket embracing 80 the revoluble cylindrical casing at a point in rear of the opening therein leaving the perforated end of the cylinder overhanging and extending beyond the clamp and lead wires extending from the other end of the cylindrical casing, substantially as described. 85

In testimony whereof, I affix my signature.

THOMAS MARSHALL SMITH.

Copies of this patent may be obtained for five cents each, by addressing the "Commissioner of Patents, Washington, D. C."
